CLAIM

The ornamental design for a magnetic gun mount, as shown and described.

DESCRIPTION

FIG. 1 is a perspective view of a magnetic gun mount, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines and the areas within them in the drawings depict portions of the magnetic gun mount that form no part of the claimed design.
